SPECIFICATION forming part of Design No. 21,032, dated September 15, 1891.

Application filed August 5, 1891. Serial No. 401,782. Term of patent 3½ years.

To all whom it may concern:

Be it known that I, CHARLES BOOZE, a citizen of the United States, residing at the city of Buffalo, in the county of Erie and State of New York, have invented and produced a new and original Design for Wall-Paper, of which the following is a specification.

The leading feature of my design consists of arabesque scrolls and flowers of style Louis XVI, fancifully entwined and modeled in relief upon a background composed of parallel ribs, also in relief and as illustrated in

the accompanying drawing. The scrolls cover the surface of the paper, and the latter may be bronzed or embossed on any desired colored ground or printed paper.

What I claim is—

The design for wall-paper herein shown and described.

Witness my hand this 31st day of July, 1891. 20
CHARLES BOOZE.
